UNITED STATES PATENT OFFICE

2,607,877

HEATING SYSTEM

Edwin Fenton Stevens, St. Paul, Minn.

Application April 4, 1947, Serial No. 739,476

3 Claims. (Cl. 219—38)

1

My invention relates to a new method and apparatus for furnishing heat where electric power is available, utilizing the electronic heat generated by and released through infra-red tubes, through direct, indirect, diverted, thermo-static and manual controls.

It is the object of the present invention to provide a method and apparatus for supplying heat without accompanying smoke, gas and odor, and which is promptly available through mechanical installation. This installation is such that no chimney, stack, exhaust flues or ventilator is required. The necessary heat volume may be produced thereby at low cost of installation and operation.

A feature of the present invention resides in the safety of the apparatus employed. In view of the fact that no fire is necessary, much of the danger of explosion and damage resulting from fire is obviated.

A feature of my invention resides in the fact that the electronic heat generating means is capable of use in numerous types of devices. My heating means may be employed in steam boilers, as well as hot water boilers, and hot air furnaces. My heating unit may be employed to a hot water heater, or to a register heater which may be used either in a wall or floor. My heating means may be embraced in stoves, radiators, or fire places. My heating unit has also been found useful in salamanders and may be employed as surface or submerged type tank heaters. The units may be used in buildings of all types as well as on trains, street cars, automobiles, airplanes and vessels of various types.

These and other objects and novel features of my invention will be more clearly and fully set forth in the following specification and claims.

In the drawings forming a part of my specification:

Figure 1 is a cross sectional view through a hot air heater showing a typical construction thereof.

Figure 2 illustrates a type of hot water, or hot air furnace showing a duct extending through the heating chamber of the furnace through which the heating medium may flow.

Figure 3 is a cross sectional view through a hot water heater showing the construction thereof.

Figure 4 is a plan view of a wall or floor register type heater showing a heating unit positioned inwardly or beneath a grating through which the heat may pass.

Figure 5 is a cross sectional view of the register heater illustrated in Figure 4 showing the general construction thereof.

Figure 6 is a view similar to Figure 5 showing a double type register heater which is designed to direct heat through grills or grids on opposite sides thereof.

Figure 7 is a cross sectional view through a heating unit or salamander which is designed to serve a space heater.

2

Figure 8 is a cross sectional view through a tank heater showing a construction in which the heating unit is submerged within the liquid to be heated.

Figure 9 is a sectional view through a liquid heater showing a heating unit of the surface type designed for use for heating surrounding liquid.

Figure 10 is a front elevational view of an imitation log which is adjustably supported to serve as a heating unit in a fire place or the like.

Figure 11 is a cross sectional view through the log construction of Figure 10.

Figure 12 is an elevation view of a radiator showing my heating units embodied therein.

Figure 13 is a view of the heating unit used in the radiator of Figure 12.

Figure 14 illustrates a modified form of heating unit which may be used in place of the structure shown in Figure 13.

Figure 15 is a front elevational view of a portable heater which may be used as a space heater for a particular heating operation.

Figure 16 is a cross sectional view through the structure illustrated in Figure 13.

In Figure 1 of the drawings I disclose a furnace A which embodies infra-red tubes capable of producing heat. The furnace A includes a base 10 having a hollow body 11 mounted thereon. The body 11 includes a lining wall 12, an outer wall 13, and intermediate insulating means 14 therebetween. A heat conducting outlet 15 extends through the closed top 16 of the body 11 and is designed to conduct heat to any suitable location either close to or distant from the furnace A. An air inlet pipe 17 is provided at the lower extremity of the body leading into the furnace A. Air may enter through this inlet 17 into the interior of the body 11 and be allowed to flow through the outlet 15 after being heated to the necessary extent.

A substantially U-shaped support 19 is provided within the body 11 on which is mounted a series of spaced sockets 20. Infra-red heat tubes 21 are mounted in the sockets 20 and are connected by suitable wiring to the plug 22 which may be plugged into any suitable supply of electrical current. When the plug 22 is properly connected to a current supply the tubes 21 may be energized, producing heat directed toward the interior of the furnace body 12. The air passing through the interior of the furnace is heated by these tubes and passes out through the outlet 15.

In Figure 2 of the drawings I disclose a furnace B which may be a steam or water boiler or may comprise a hot air furnace. The furnace B includes a base 23 having mounted thereupon a body 24. The body 24 is formed of insulated walls which may if desired form a normally sealed inner chamber 25. A fluid passage 26 has its inlet at 27 and extends in a tortuous path to the outlet 28.

A support 29 is secured to the bottom of the

chamber 25 and supports a series of spaced sockets 30. These sockets 30 support spaced infra-red heat tubes 31 which produce heat sufficient to warm the interior of the body 24 or heat the entire chamber 25. As the heating fluid passes through the passage 26 it is heated to the desired extent and is allowed to flow through the outlet 27.

In Figure 3 of the drawings I disclose a hot water heater indicated in general by the letter C. This heater includes tubular vertical walls 32 which are preferably insulated so as to allow a minimum of heat to escape. The walls 32 enclose a cylindrical tank 33 designed to contain water or any other desired fluid. A liquid inlet 34 is provided near the bottom of the tank 33 and a liquid outlet 35 is provided near the top thereof.

Within the walls 32 and below the level of the tank 33 I provide a support 34 on which are secured a series of spaced sockets 35. Infra-red heat tubes 36 are supported in these sockets 35 and are designed to direct heat against the lower end of the tank 33. The liquid within the tank is accordingly quickly heated and may be removed through the outlet 35 for any desired use. The tubes 36 are connected by suitable wiring to a plug 37 which may be inserted in any common socket secured to a source of power supply. The current from the power supply is directed to the bulbs 36 to heat the tank 33. A suitable thermostatic switch 39 may be located in the circuit between the plugs 37 and the tubes 36 to control the temperature of the tank.

In Figures 4 and 5 of the drawings I disclose diagrammatically a heating unit which in substance comprises a hollow enclosure having a grid or grill covering the same and which may be recessed into a wall or floor. The register heater D illustrated in these figures includes a base panel 40 and enclosing wall panels 41, providing a rectangular enclosure having an open side. A grill or grid 42 is mounted in this side so as to provide a foraminous covering for the register through which heat waves may pass.

A supporting panel 43 is secured adjacent the base panel 40 and supports a series of spaced sockets 44. Infra-red heat tubes 45 are provided in the sockets 44 to direct heat through the grid or grill 42.

The tubes 45 are electrically connected in parallel by means of suitable wires which extend through a switch 46 to a suitable source of current supply. When the switch is on, electricity is supplied to the infra-red heat tubes 45, directing heat through the grill or grid 42.

In Figure 6 of the drawings I disclose a double type register heater E which is somewhat similar to the heater D just described. The heater E includes a rectangular frame 48 which is open at both ends and which is equipped with a center panel 47. A pair of parallel supports 49 are mounted on opposite sides of the panel 47 and each support 49 has secured thereto a series of spaced sockets 50. Infra-red heat tubes 51 are mounted in the sockets 50 to direct heat outwardly from the center panel 47. A grill or grid 52 is provided in each end of the enclosure 48 so as to provide a foraminous panel through which heat waves may pass. A switch 53 is connected by suitable wires to the various tubes 51 which are wired in parallel. A similar switch 54 is connected by suitable wiring to the heat tubes 51 of the other panel 49 so as to provide a means of controlling the current flow thereto. The switches 53 and 54 are connected to a

suitable current supply source which may energize the tubes 51 and direct heat out of either of the grids or grills 52 when desired.

In Figure 7 of the drawings I disclose a heater F which may serve as a space heater or salamander. This heater F includes tubular insulated side walls 55 which are closed at their lower end by an insulated bottom 56. A cone-shaped deflector 57 is peripherally secured at 59 to the upper edges of the walls 55. Angularly spaced openings 60 are provided through the wall 55 near the upper extremity thereof so that heat generated within the chamber 61, defined by the walls 55, the bottom 56 and the top 57, may flow.

A support 62 is provided adjacent the bottom 56 and this support has thereupon a series of spaced sockets 63. Infra-red heat tubes 64 are supported in the sockets 63 and are properly directed to heat the interior of the heater F. Heated air is directed through the apertures 60 and the cone-shaped deflector 57 also serves as a heat transfer means to heat air above the cone-shaped tube 57.

Figure 8 illustrates a liquid heater G of the immersion type embodying my heating unit. The tank 65 is provided, which may or may not be open at its upper end as illustrated. A chamber 66 having vertically extending walls 67, a closed bottom 69 secured to the lower ends of the walls 67 and a closed top secured to the upper ends of the walls 67, is supported within the outer tank 65. A tubular passage 71 extends through the closed top 70 and extends above the level of the side walls 72 of the tank 65. Wires 73 extend through this tubular passage 71 into the interior of the chamber 66. A support 74 is secured within the chamber 66 near the top 70 thereof and supports a series of spaced sockets 75. Infra-red heat tubes 76 are supported in the sockets 75. These heat tubes 76 are connected in parallel by the wires 73 to a plug 77 which may be secured to any suitable socket. When the tubes 76 are energized heat is created which is directed against the closed bottom 69 acting to heat the interior of the chamber 66 and to heat the liquid surrounding this chamber within the tank 65.

Figure 9 illustrates a liquid heater H. This heater H includes an outer tank 79 having side walls 80, a closed bottom 81, and an open top which may be equipped with a cover if desired. A hollow receptacle 82 extends into the tank 79 and is supported in spaced relation to the bottom 81 thereof by means of legs or supports 83. The inner tank 82 is provided with side walls 84 and a closed bottom 85 attached thereto. A support 86 is provided near the top of the tank 82 and this support has a series of spaced sockets 87 mounted thereon. The sockets 87 support infra-red heat bulbs 89 or the like, which are preferably positioned to direct heat downwardly toward the tank bottom 85. The tubes or bulbs 89 are connected in parallel to a pair of conductors which lead to a plug 90 designed for insertion into any electrical socket.

In Figures 10 and 11 of the drawings I disclose a heater J which may be placed in a fire place or the like to produce a decorative appearance as well as to produce heat. The heater J includes a base 91 having a pair of spaced upwardly extending standards 92 thereon. A tubular body 93 simulating in outward appearance a log or length of wood is pivotally supported at 94 to the standards 92.

The tubular body 93 has a support 98 therein extending longitudinally of the body 93. The support 98 has a series of spaced sockets 95 thereon which are designed to accommodate infra-red heat tubes 96. These tubes are inserted through spaced apertures 97 in the surface of the log so that the heat waves or heat rays generated by the tubes may be directed outwardly in a radial direction.

The various heat tubes are preferably connected in parallel to a suitable source of current supply and when energized produce radiant heat. The direction in which the heat travels may be regulated by pivoting the log body 93 about the aligned pivots 94.

In Figure 12 of the drawings I disclose a heater K which simulates a radiator in outward appearance. The radiator K is formed of a series of hollow sections 97 connected together by bolts 99 or other suitable fastening means. A transverse passage 100 extends through all of the sections 97, forming a common connection between these sections. An aperture 101 is provided at one end of the radiator and a plug 102 is provided for normally closing this opening. The plug 102 as illustrated in both Figures 12 and 13 has an elongated support 103 connected thereto. A series of spaced upwardly projecting brackets 104 are mounted on the support 103. Sockets 105 are provided on each of the brackets 104 and infra-red heat tubes 106 are supported in the sockets 105. The heat tubes 106 are preferably connected in parallel to a pair of conductors which extend through the plug 102 to a suitable source of current supply. When energized the bulbs 106 generate heat which heats the entire interior of the hollow sections 97.

In Figure 14 of the drawings I disclose an infra-red tube support which may be used in place of the support previously described. In this arrangement I provide a plug 107 similar to the plug 102 and which may be substituted therefor. An elongated support 109, similar to the previously described support 103, is attached to the plug 107. A series of sockets 110 are mounted in spaced relation upon the support 109. Infra-red heat tubes 111 are mounted in the sockets 110. The heat generated by the tubes 111 is directed in a generally vertical direction, whereas the heat generated by the bulb 106 is projected in a horizontal direction.

In Figures 15 and 16 of the drawings I disclose a portable heater L which may be moved from room to room if desired. The heater L includes a base panel 112 having upwardly extending spaced parallel sides 113 at either end thereof. A top panel 114 is connected to the upper ends of the sides 113 and a rear panel 115 is provided on the rear of the frame. A front shield 116 having a curved under-surface 117 is provided at the upper edge of the enclosure.

A rectangular aperture 119 is provided in the rear panel 115 and an adjustable panel 120 is arranged to fill this aperture. The panel 120 is pivotally supported at 121 to a supporting bracket 122 connected to the rear surface of the panel 115. The pivot joint 121 is a universal connection so that the panel 120 may be pivoted out of a vertical plane or transversely.

The panel 120 is provided with a series of spaced sockets 123 thereon which are designed to accommodate infra-red heat tubes 124. The heat tubes 124 are arranged in generally parallel relation so that the heat generated thereby may be projected in any desired direction.

It will be noted from the foregoing description that my infra-red heat tubes may be used in numerous ways to produce a heater for liquid or air. The heat is in every case generated from a convenient source of supply of current which actuates infra-red heat tubes.

In accordance with the patent statutes, I have described the principles of construction and operation of my heating system, and while I have endeavored to set forth the best embodiments thereof, I desire to have it understood that these are only illustrative thereof, and that obvious changes may be made within the scope of the following claims without departing from the spirit of my invention.

I claim:

1. A heater including an enclosure, a support within said enclosure, said support comprising a U-shaped member having generally parallel sides arranged near opposite sides of the enclosure and, a base extending along the bottom of said enclosure, a series of infra-red light bulbs secured to said support, certain of said lights being secured to the sides of said support and being directed inwardly toward one another, and infra-red bulbs on the base of said support directed upwardly, and a suitable source of power supply for said light bulbs.

2. A heating system including a housing including a closed chamber, a fluid conduit extending into said chamber at the lower extremity thereof and extending upwardly in said chamber, said fluid conduit extending from said chamber near the upper extremity thereof, a support within said chamber adjacent the lower extremity thereof, a series of infra-red ray tubes supported by said support, and means connecting said tubes to a suitable source of fluid supply, said tubular conduit forming a fluid circulating system through which fluid may flow, said conduit being in heat exchange relation with the air within said chamber.

3. The structure described in claim 2 and in which the conduit follows a tortuous passage through said chamber.

EDWIN FENTON STEVENS.
